UNITED STATES PATENT OFFICE.

JOHN A. RUFFIN, OF MIDDLETOWN, CONNECTICUT, ASSIGNOR TO THE NOISELESS TYPE-WRITER COMPANY, OF MIDDLETOWN, CONNECTICUT, A CORPORATION OF CONNECTICUT.

TYPE-WRITING MACHINE.

1,242,244.

Specification of Letters Patent. Patented Oct. 9, 1917.

Application filed March 31, 1916. Serial No. 87,938.

To all whom it may concern:

Be it known that I, JOHN A. RUFFIN, a citizen of the United States, residing at Middletown, in the county of Middlesex and 5 State of Connecticut, have invented certain new and useful Improvements in Type-Writing Machines, of which the following is a full, clear, and exact description, such as will enable others skilled in the art to 10 which it appertains to make and use the same.

This invention relates to typewriting machines, and more particularly to improved type carriers and type sets therefor.

15 One of the objects of the invention is to provide a simple and practical type carrier capable of expeditious adjustment to present alternative type characters for printing.

20 Other objects and advantages will be in part noted hereinafter in connection with the description of the accompanying drawing, wherein is represented an exemplary embodiment of the invention.

Referring more particularly to the drawing, there are shown parts of one type action, including a pivoted bell crank lever 1 having its long arm medially pivoted to a floating link 2 at the forward end of which is arranged a leaded weight 3 and the rear 25 end of which is pivoted to the depending arm 4 of a T-lever 5. The bell crank lever 1 and T-lever 5 are both pivoted to a supporting bracket 6 mounted for adjustment on a cross piece 7 of the machine frame. 30 The opposite end of the T-lever 5 is pivotally connected with a link 8, in turn connected pivotally to a medial cross member of a longitudinally movable type carrier 9.

35 The bell crank lever 1 is adapted for actuation by a key lever of the machine to carry the long arm of the lever in overlapping alinement to the rear arm of the floating link 2 and to extend the top arm of the T-lever 5 into alinement with the link 8, 40 thereby forming two straightened toggles to limit the movement of the type carrier 9 toward the platen. The levers 1 and 5 are of duplex form to respectively straddle lever 5 and floating link 2 when actuated, to 45 transmit movement to the type carrier under controlled speed and pressure.

The type carrier 9 is preferably of the skeleton form shown and mounted for reciprocation between a bed plate 10 and a top plate 11, being guided by registering 55 grooves 12 in guide plates 13 and 14. At each end of the type carrier there is provided a set of type characters 15 and 15' faced with three type to print in different case positions of the shiftable platen. The 60 type pieces 15, 15' are riveted or otherwise solidly fixed to the type carrier, and are secured thereto in relatively opposite positions. The type carrier 9 is relatively thin and is freely pivoted to the double arm link 65 8 by screw pivot 16 so that the type carrier may be swung when desired and reversed in position to bring the type piece 15' at the opposite end into action for printing. In this manner the type carrier is provided 70 with two separate sets of characters which may be alternatively used when, for example, one set has become worn or defaced. A further advantage of the structure described resides in its adaptability for printing 75 in different languages, since it will be apparent that one set of English type may be used and one set of characters for a foreign language. The change from one to the other is also readily effectible, it being necessary merely to remove top plate 11 and swing the type carriers reversely, and then 80 replace the top plate.

The invention is shown in the drawing as incorporated in a noiseless typewriter. 85 It is to be understood, however, that certain features thereof are applicable as well to various other styles of machines.

Having described my invention, what I claim as new and desire to secure by Letters Patent is:

1. In a typewriting machine, in combination, a type carrier having a plurality of sets of oppositely disposed type, a power transmitting member freely pivoted to said carrier, and spaced guides for said carrier, one of said guides being removable for permitting reversal of said carrier to present selective type to print. 95

2. In a typewriting machine, a platen, a longitudinally movable skeleton type carrier, a power transmitting link medially 100

connected thereto, and separate sets of type rigidly secured to opposite ends of said carrier for alternative coaction with said platen.

3. In a typewriting machine, a reciprocal type carrier mounted for movement between supporting and guiding plates, a plurality of sets of type permanently and rigidly attached to said type carrier, and means permitting reversal of said carrier

for utilizing either of said sets of type to 10 effect printing.

In testimony whereof I affix my signature, in the presence of two witnesses.

JNO. A. RUFFIN.
